CLAIM

The ornamental design for a fishing rod holder, as shown and described.

DESCRIPTION

FIG. 1 is a front elevational view of a fishing rod holder, showing my new design;

FIG. 2 is a rear elevation view thereof;

FIG. 3 is a right, side-elevational view thereof;

FIG. 4 is a left, side-elevational view thereof;

FIG. 5 is a top plan view thereof; and,

FIG. 6 is a bottom plan view thereof.

The broken line showing of environment in FIGS. 1, 3–6 is for illustrative purposes only and forms no part of the claimed design.
